UNITED STATES PATENT OFFICE.

JEROME F. McCALL, OF PHILADELPHIA, PENNSYLVANIA.

BOX.

1,104,063.

Specification of Letters Patent.

Patented July 21, 1914.

Application filed February 5, 1914. Serial No. 816,657.

To all whom it may concern:

Be it known that I, JEROME F. McCALL, a citizen of the United States, residing at Philadelphia, in the county of Philadelphia and State of Pennsylvania, have invented a new and useful Improvement in Boxes, of which the following is a specification.

The principal object of the invention is to provide a folding box which can be made complete from a single blank and is therefore comparatively inexpensive to make, which can be easily folded for use, and which is strong and stiff and well stayed when arranged in position for use.

15 The invention is capable of many embodiments among which I have chosen several which I believe will be sufficient for explanation and have illustrated them in the accompanying drawings in which—

20 Figure 1, is a top or plan view of a blank which can be folded into a box member embodying features of the invention. Fig. 2, is a plan view illustrating the operation of folding the blank. Fig. 3, is a side view illustrating the same thing. Fig. 4, is a cross sectional view somewhat in perspective and with parts broken away, illustrating a box member embodying features of the invention. Fig. 5, is a sectional view

30 taken on the line 5—5, of Fig. 4. Fig. 6, is a view somewhat similar to Fig. 2, and illustrating the employment of staples. Fig. 7, is a view of a part of a blank which when folded constitutes a box member embodying

35 a modification of the invention. Fig. 8, is a cross-sectional view somewhat in perspective illustrating the box member made from the blank shown in Fig. 7, but not quite completed. Fig. 9, is a view similar to Fig. 40 8, with parts broken away, showing the box member completely assembled. Fig. 10, is a view of a blank which, when folded, constitutes a box member embodying another modification of the invention. Fig. 11, is a

45 view showing the blank of Fig. 10, partly folded, and Fig. 12, is a longitudinal section showing a box member made from the blank of Fig. 10.

By box member is meant either a lid or a tray the depth or height of which may be increased or diminished.

The end 1, is provided with an inturned fold 2. The side 3, is provided with an extension 4, Figs. 1-6, 4^a, Figs. 7-9, and 4^c, Figs. 10-12, and this extension is arranged between the parts of the fold. On the ex-

tension there is an inward flap 5, Figs. 1-6, 5^a, Figs. 7-9, and 5^c, Figs. 10-12, and this flap engages the inner part of the inturned fold and constitutes a stay. As shown in Figs. 1-9, the extension is creased and doubled as at 6, whereas as shown in Figs. 10-12, the extension 4^c, is not creased and doubled but is merely turned in between the parts of the inturned fold 2. It may be desirable to use staples or fastenings at the doubled and creased part of the extension and these are indicated at 7, in Fig. 6. The flaps may be variously arranged on the extensions and according to their arrangement on the extensions their position in the box member may be somewhat varied; but in every case they project inward substantially parallel with the inner face of the body of the box member, sometimes being in contact with that face, Figs. 1-6 and 10-12, and sometimes being above that face, Figs. 7-9. The flaps 5, Figs. 1-6, are prolongations of the sides. This is true also of the flaps 5^a in Figs. 7-9. In Figs. 10-12, the flaps 5^c project laterally from the extensions or sides. In Figs. 1-6 and 10-12, the flaps extend to the bottom of the box member as do also the folds 2, and this construction is suitable for comparatively shallow box members.

In the construction shown in Figs. 7-9, the fold 2, does not extend to the bottom of the box member and the inward flap 5^a is not near the bottom of the box member but passes through the creased or doubled portion 6, so that its inwardly projecting end can engage the fold. The construction last described is suitable for deep trays such as hat boxes because the saving of material effected by shortening up the fold 2, may be substantial.

The extension, the flap, and the inner part of the fold, as has been said, engage one another. For this purpose tongues 8, and 8^c, are shown in Figs. 2 and 11, on the inner part of the fold. Tongue receiving openings 9, 9^a and 9^c, Figs. 2, 8 and 11, are shown in the flaps.

The engagement of the inner part of the fold with the flap when the parts are combined and arranged as described provides an efficient stay which imparts to the box member firmness and rigidity. Since the entire box member can be made in one piece it follows that its production is comparatively inexpensive.

To fold the blank in Figs. 1-6, the sides

are turned into erect position, the extensions are turned in onto the sides, the sides are folded along the crease 6, thus bringing the end into erect position with the flaps 5, extending inward in contact with the inner face of the box member. The fold 2, is then turned in and its tongues 8, are made to engage the openings in the flaps 5, and so the box member is locked. In Figs. 7-9, the operation is the same except that the flaps 5^a, pass through the parts but they extend parallel with the inner face of the box member and inward. In Figs. 10-12, the operation is the same as described in connection with Figs. 1-6, except that the creasing at the corners is omitted. The flaps 5^c, project inward in contact with the inner face of the box member.

What I claim is:

20 1. In a box member the combination of ends and sides in folded relation at the cor-

ners, an inturned fold on the end, and a flap integral with the side and passing back of the corner and end folds making five plies and projecting inward past said folds substantially parallel with and detached from the inner face of the body of the box member and engaging the inner part of the in-turned end fold and constituting therewith a lock. 25

2. In a box member the combination of an end having an inturned fold, and a side passing back of said fold and having an integral flap extending inward past the fold and arranged substantially parallel with 30 and free from the inner face of the body of the box member and engaging the inner part of the inturned fold to constitute a lock. 35
